(57) **CLAIM**

The ornamental design for an air conditioner, as shown and described.

DESCRIPTION

The file of this patent contains at least one drawing/photograph executed in color. Copies of this patent with color drawing(s)/photograph(s) will be provided by the Office upon request and payment of the necessary fee.

1. Air conditioner
- 1.1 : Front
- 1.2 : Left
- 1.3 : Right
- 1.4 : Top
- 1.5 : Bottom
- 1.6 : Perspective

1 Claim, 6 Drawing Sheets
